UNITED STATES PATENT OFFICE

116,840

DESIGN FOR AN ELECTRIC WELDING MACHINE

Charles Eisler, South Orange, N. J.

Application December 16, 1938, Serial No. 81,814

Term of patent 14 years

To all whom it may concern:

Be it known that I, Charles Eisler, a citizen of the United States, residing in South Orange, in the county of Essex and State of New Jersey, have invented a new, original, and ornamental Design for an Electric Welding Machine, of which the following is a specification, reference being had to the accompanying drawing, forming part thereof.

In the drawing, Figure 1 is a perspective view of an electric welding machine. Figure 2 is a side view of an electric welding machine and Figure 3 is a top view of the electric welding machine, showing my new design.

I claim:

The ornamental design for an electric welding machine, as shown.

CHAS. EISLER.
